DESIGN FOR A PICTURE FRAME

Hedwig Heilbroner and George R. Arons,
New York, N. Y.

Application August 27, 1945, Serial No. 121,674

Term of patent 3½ years

(Cl. D29—20)

To all whom it may concern:

Be it known that we, Hedwig Heilbroner and George R. Arons, citizens of the United States of America, residing in the city, county, and State of New York, have invented a new, original, and ornamental Design for a Picture Frame, of which the following is a specification, reference being had to the accompanying drawing, forming a part thereof.

Fig. 1 is a isometric view of a picture frame showing our design, and

Fig. 2 is a partial sectional view of the picture frame taken along line 2—2 of Fig. 1.

We claim:

HEDWIG HEILBRONER.
